UNITED STATES PATENT OFFICE.

WILLIAM H. HARING, OF SUFFERN, NEW YORK, ASSIGNOR TO AMERICAN BRAKE SHOE & FOUNDRY COMPANY, OF MAHWAH, NEW JERSEY, A CORPORATION OF NEW JERSEY.

STEEL BACK AND LUG FOR BRAKE-SHOES.

1,102,582.

Specification of Letters Patent.

Patented July 7, 1914.

Application filed June 11, 1913, Serial No. 772,964. Renewed May 14, 1914. Serial No. 838,621.

To all whom it may concern:

Be it known that I, WILLIAM H. HARING, a citizen of the United States, and a resident of Suffern, in the county of Rockland and 5 State of New York, have invented a new and Improved Steel Back and Lug for Brake-Shoes, of which the following is a full, clear, and exact description.

This invention relates to brake shoes, and 10 particularly to that part commonly known as steel backs and lugs, and has for an object to provide an improved steel back and lug of simple, strong structure, and one that will not crack.

15 Another object of the invention is to provide a steel back structure an d lug, with a body portion acting as the back and a winding of pliable metal designed to act as the lug, or the reinforcement for the lug.

20 A still further object of the invention is to provide a steel back with a wrapping of steel at substantially the central part, whereby when a shoe is cast on a steel back some of the metal may be caused to 25 surround entirely, or partially surround the wrapping, whereby the shoe is backed up with a plate of steel and the lug is reinforced with a strip or plurality of strips of steel.

30 In carrying out the objects of the invention, a steel back is provided formed either with a straight central portion or with a reduced central portion, designed to receive a winding of pliable metal, as for instance 35 a strap steel, or other suitable metal. In place of the strap steel, steel wire, or other pliable wire may be used. Also in the formation of the steel back, the reduced central portion may be bent outwardly for presenting 40 a recess for receiving the coil of metal forming the lug or the reinforcement of the lug when the lug is formed of cast material.

A practical embodiment of the invention 45 is represented in the accompanying drawings forming a part of this specification in which similar characters of reference indicate corresponding parts in all the views.

Figure 1 is a perspective view of a steel back and reinforcing lug embodying the 50 invention; Fig. 2 is a longitudinal vertical section through a shoe, with the steel back and lug embodying the invention arranged therein; Fig. 3 is a section through Fig. 2 on the line 3—3; Fig. 4 is a perspective view of a slightly modified form of the in-

vention to that shown in Fig. 1; Fig. 5 is a longitudinal vertical section through the brake shoe with the steel back and lug disclosed in Fig. 4 arranged in place; Fig. 6 is a section through Fig. 5 on the line 6—6; 60 and Fig. 7 is a view similar to Fig. 5 except that the same shows a slightly modified form of steel back.

Referring to the accompanying drawings by numerals, 1 indicates a steel back provided with apertures 2 and 3 at each end. If desired, a single aperture could be used, though a plurality is preferred. Midway between the ends of the steel back 1 is a reducing portion 4 which is provided with 70 a pressed out, or pressed up portion 5, whereby the winding 6 of strap steel or other flexible metal, may be placed in position; as shown in Fig. 1, without an appreciable amount thereof projecting below the face 75 of the steel back 1. The winding 6 may be formed with a single winding or with any desired number, without departing from the spirit of the invention, the end 7 of the winding being preferably clamped over the 80 pressed up portion 5 so as to better hold the winding 6 in position previous to casting. After the steel back and winding 6 which forms the lug or the reinforcement, 85 has been properly constructed and assembled, as shown in Fig. 1, the same is in condition to have the cast metal applied. After the cast iron, cast steel, or other metal has been cast in place, as shown in Fig. 2, the 90 brake shoe is in condition for use. In Fig. 2 the steel back 1 is shown as being entirely embedded or submerged in the rear part of the shoe 8, but it will be evident that the rear face of the steel back 1 could be flush with the back of the shoe 8 if desired, without departing from the spirit of the invention. It will also be observed that the lug 9 of shoe 8 surrounds or has embedded 95 therein the winding 6, whereby the lug is reinforced and even though the same cracks 100 it cannot fall off.

In Figs. 4, 5, and 6 a slightly modified form of the invention is disclosed. Referring to these figures, the steel back 1 has arranged centrally thereof windings 10, 105 formed of steel wire, or other flexible wire, for providing a reinforcement for the lug 11 of shoe 12. Aside from the windings 10 being of wire, the structure is the same as the preferred form of the invention so that 110

the same reference numerals will be used for the same parts.

In Fig. 7 is disclosed a further slightly modified form of the invention, in which 5 the center 13 is perfectly straight so that the steel back 1' is formed in the arc of a circle from one end to the other without a break. In forming the steel back, the same is preferably formed on the arc of a circle 10 in all forms of the invention, but transversely it is preferably formed flat or straight. In the form of the invention shown in Fig. 7, a shoe 14 is provided with a lug 15, which may have as its reinforcement windings 10, as shown, or windings 15 similar to windings 6.

It will be understood that the center of the steel back in any of the forms of the invention could be made of the same width 20 as the remaining part of the steel back, without departing from the spirit of the invention.

Having thus described my invention I claim as new and desire to secure by Letters 25 Patent:—

1. A steel back comprising a single strip of metal for forming the body of the steel back, and a winding of metal for forming a lug reinforcement.
2. A back for a brake shoe formed from a strip of metal provided substantially centrally with a transverse winding of metal.
3. A back for brake shoes formed from a ductile plate having a raised central portion, and a winding of ductile metal encircling said raised portion and with portions thereof spaced therefrom for providing a lug reinforcement.
4. A back for brake shoes formed from a

single plate of ductile metal, and a transverse winding of ductile strips of metal, said transverse winding presenting a lug reinforcement.

5. A back for brake shoes formed from a strip of ductile metal having a reduced 45 pressed out portion and a substantially ring member encircling said pressed out portion said ring member comprising a plurality of windings of a strip of metal.

6. A back for brake shoes formed from a strip of ductile metal, said strip being reduced centrally, and said central portion being offset, and a winding of ductile metal surrounding said offset portion, said winding presenting substantially a ring whereby 50 55 a lug reinforcement is formed.

7. A back for a brake shoe formed from a strip of ductile metal, and a substantially ring structure arranged centrally of said strip and surrounding the same, said ring structure comprising a plurality of strips 60 of ductile metal.

8. A back for a brake shoe formed from a strip of metal, and a ring structure arranged centrally of the strip of metal, said 65 ring structure comprising a plurality of superimposed strips of ductile metal.

9. A cast brake shoe having a steel back, and a coiled ductile reinforcement arranged 70 in the lug of the brake shoe.

In testimony whereof I have signed my name to this specification in the presence of two subscribing witnesses.

WILLIAM H. HARING.
